UNITED STATES PATENT OFFICE.

KURT SEIFFERT, OF LOS ANGELES, CALIFORNIA.

MULTIPLICATION DEVICE.

Application filed March 27, 1924. Serial No. 702,378.

My invention relates to and has for its purpose the provision of a simple, inexpensive and durable device by which any number can be multiplied by any one of the digits 5 and the correct product obtained.

I will describe only one form of multiplication device embodying my invention, and will then point out the novel features thereof in claims.

10 In the accompanying drawings

Figure 1 is a view showing in top plan, with a portion thereof broken away, one form of multiplication device embodying my invention;

15 Figure 2 is a longitudinal sectional view taken on the line 2—2 of Figure 1;

Figures 3 to 6, inclusive, are sectional views taken on the lines 3—3, 4—4, 5—5 and 6—6, respectively, of Figure 1.

20 Similar reference characters refer to similar parts in each of the several views.

Referring specifically to the drawings, my invention in its present embodiment comprises a base board 15 to the under side of 25 which are secured strips 16 so as to support the device in slightly elevated position. This base board 15 constitutes the bottom of a casing, including side members 17, an end member 18 and a top or cover 19, the latter being removably secured by means of screws 20 or other suitable fastening members. The side walls 17 terminate short of one end of the base board 15 and are tapered to correspond to vertical partitions 21 arranged 30 between the tapered ends. These vertical partitions 21 are arranged at spaced intervals across the base board and have their lower edges disposed in grooves 22 formed in the base board 15, as clearly shown in Figure 6. The space between any two adjacent vertical partitions 21 is divided into a plurality of superposed compartments or channels by means of horizontal partitions 23, which are welded or otherwise secured to 35 the vertical partitions so as to occupy fixed positions with respect to the latter. These horizontal partitions terminate at their rear ends at a common point, as clearly shown in Figure 2, while at their forward ends they 40 terminate at such points that they are disposed in stepped relation to correspond to the forward edges or ends of the vertical partitions 21. The inclined front edges of the partitions 21 are formed with flanges 45 24 (Figures 3 and 6) which co-operate with each other to prevent displacement of ele-

ments from the uppermost compartments or channels, as will be best understood from the operation.

The compartments or channels between 50 any two adjacent vertical partitions constitute a group in which strip elements 25 are adapted to slide, such elements bearing numbers which are adapted to constitute the product. These strip elements are made up 55 of flexible strips of celluloid or other suitable material and have connected to their rear ends clips 25^a in which are engaged elastic members 26, extending through guide openings formed in an abutment plate 27 60 extending transversely within the casing, and secured to posts 28. The elastic members serve to yieldably urge the strips into concealed position within the channels, but the strip elements can be withdrawn from 65 the channels into display position and against the action of the elastic members 26. The forward ends of the strip elements are provided with metallic guide members 30 70 within which are exposed numerals adapted 75 to be at all times displayed irrespective of the position of the strip elements and constituting the digits of the multiplicand. In the normal position of the strip elements 25 the metallic guide members 30 are disposed 80 in stepped relation, as clearly illustrated in Figures 1 and 2, with the digits of the multiplicand at all times visible so that any desired strip element can be selected.

Any one of the strip elements is adapted 85 to be moved to projected or display position by engaging a pointed instrument S shown within a holder H secured to the cover plate 19 and applied within the guide members, as shown in dotted lines in Figure 5. The outward movement of the strip element is limited by means of an abutment strip 32 (Figure 5) secured to the forward end of the base board 15. As the strip element is moved to display position, a latch pin 33, normally 90 urged upwardly by a spring 34, engages the under side of the guide member 31, which is provided with an opening 36 constituting a keeper and co-operating with the latch pin to hold the strip element in projected or display position against the action of the elastic member 26. It will be of course understood that one latch pin 33 and spring 34 is provided for each group of strip elements 25, and as all of the strip elements of all of the 95 groups are provided with guide members 30, it will be clear that any one strip element of

any group can be held in display position by the latch means described. These several latch means can be simultaneously actuated to release the strip elements through the medium of a tripping bar 37 mounted for vertical movement through the base board and abutment strip by means of posts 38 secured to the bar 37 and to a lower bar 38^a by means of screws. The lower bar has engagement with the free ends of the springs 34 so that by depressing the tripping bar 37 the several springs will be flexed downwardly, as indicated in dot and dash lines in Figure 5, to depress the latch pins 36 free of the guide members 30, thereby releasing the strip elements and allowing them to be drawn to concealed position under the action of the elastic members 26. A cover strip 39 is secured to the abutment strip 32, and this strip is recessed at its forward edge as indicated at 40 to allow the instrument S to occupy proper position in moving any one guide member into latching engagement with the corresponding pin 36.

As clearly shown in Figure 1, the strip elements of any one group bear multiplicand digits ranging from "0" to "9" and consecutively from the lowermost strip element to the uppermost. All of the strip elements of each group also bear what may be termed product digits in that they co-operate to give the product of a multiplicand formed by the multiplicand digits on the strip elements and any one of the multiplier digits arranged on stationary strips 41 secured to the base board 15, as shown in Figure 1. The zero strip elements of all of the groups merely bear ciphers, but the other strip elements bear numbers which are multiples of the multiplicand digits. For example, the strip element bearing the multiplicand digit "9" has product numerals in multiples of 9, ranging from "1" to "81", or from "9" to "81". The digits of these multiples are separated as shown in Figure 1 for the purpose of pairing or combining them with the digits of the numbers of adjacent strip elements. Those digits which are adapted to be combined with the digits of adjacent strips are provided with darkened backgrounds, as shown in Figure 1, while the background of the other digits is made light to distinguish them from the first digits.

In the projected position of the strip elements the product numerals thereon may be grouped transversely of the elements to designate the product for any particular digit of the series of multiplier digits by means of a selector strip or bar 42 provided at one end with a sleeve 43 slidably mounted upon a rod 44 fixed to the base board and casing. This sleeve 43 is rigidly connected to the selector strip 42 and because of its mounting upon the rod 44 it will be clear that the strip 65 can be adjusted longitudinally of the base

board or swung from the transverse position shown in Figure 1 to a position at one side of the member 15 in order that one may move the strip elements to displayed position. In the transverse position of the selector bar 70 any desired group of product numerals can be displayed in the slot 41^a of such bar, and simultaneously therewith the desired multiplier digit through openings 45.

In operation, all of the strip elements are 75 normally retracted to concealed position within the channels or compartments by means of the elastic members 26, and the selector bar is swung to one side so that an operator can freely manipulate the instrument S in moving the desired strip elements to projected or displayed position.

If it is now desired to multiply any one number by another, say, for example, "4209" by "5", the strip elements bearing the multiplicand digits 9, 0, 2, and 4 are successively withdrawn to projected position by the use of the instrument S until the guide members 30 are engaged by the latch pins 33, when the elements will be held in displayed 90 position. It will of course be understood that only one strip element from one group is withdrawn to displayed position, and that the four strip elements withdrawn are of the first four groups. Having moved the proper strip elements to displayed position 95 the selector bar is now swung to overlying relation to the elements and then adjusted along the rod 44 until the openings 45^a coincide with the multiplier digits 5, when, 100 within the slot 45, a group of numerals will be exposed which, when properly combined, will give the correct product. The product, which is "21,045", is obtained by considering the digit "5" of the first strip element 105 as the unit digit of the product; adding the two adjacent digits of the first and second strip elements which, in this instance, amounts to "4" and constitutes the tens digit of the product; considering the first digit 110 of the third strip element as the hundreds digit; then adding the two digits of the third and fourth strip elements, which gives the sum of "1" and constitutes the thousands digit; and finally considering the 115 second digit "2" of the fourth strip element as the ten thousands. In this manner the product of any other two numbers within the range of the device can be obtained.

After each operation the strip elements 120 can be restored to concealed position by merely depressing the trip bar 27, when the elastic members 26 will function to draw the elements into the compartment. During the return of the elements to concealed position the edges 24 of the vertical partitions 21 serve to guide the elements back into their respective compartments, the abutment plate 27 operating to limit the return movement 125 of the elements so that in their final posi- 130

tions the multiplicand digits will remain exposed to view.

Although I have herein shown and described only one form of multiplication device embodying my invention, it is to be understood that various changes and modifications may be made herein without departing from the spirit of the invention and the spirit and scope of the appended 10 claims.

What is claimed is:

1. A multiplication device comprising a plurality of elements movable to occupy either of two extreme positions, each element bearing multiplicand numerals and other numerals which are multiples of the multiplicand numerals, the digits of each multiple numeral being distinguished from each other to permit combining certain of the digits with the digits of adjacent multiple numerals of adjacent elements, and stationary elements bearing multiplier numerals whereby when those elements are moved from one extreme position to the other and bearing the multiplicand numerals composing the multiplicand of an example, the transversally alined multiple numerals of the elements as determined by the desired multiplier numeral will give the correct product when one multiple digit of each element is considered as constituting one denomination of the product, while the remaining multiple digits of adjacent elements are added to constitute the remaining digits of the product.

2. In a calculating device, a support, a row of strips carried by the support, with the strips of the row being disposed in superposed relation and of different lengths so as to underlap one another at one end, 40 the strips and the support having figures thereon bearing a mathematical relationship when alined with each other, means between the opposite ends of the strips and the support for retaining the strips in a position wherein the figures thereon are out of alinement with a numbered area of the support, and means for locking any of the strips when the latter are moved against the action of said retaining means to a position 45 wherein the figures on the strips are alined with the numbered area of the support.

3. In a calculating device, a base, horizontal and vertical partitions on the base forming a plurality of compartments arranged one above the other and graduated in length so that one end of the compartments is stepped, ribs on the base spaced to form a channel longitudinally alined with the stepped end of the compartments, 50 numeral bearing strips one in each of the compartments yieldably urged inwardly of the latter but adapted to be drawn outwardly, multiplicand numerals on the ends of the strips visible when the strips are in urged 55 position, and means for guiding the strips downwardly into the channel and upwardly 60 into their respective compartments.
